(57) **CLAIM**

The ornamental design for an instrument panel for a vehicle, as shown and described.

DESCRIPTION

This application is related to the following co-pending application, of the inventors, filed on even date herewith: application Ser. No. 29/206,692, entitled “Surface Configuration of a Center Console for a Vehicle”.

FIG. 1 is a front view of an instrument panel for a vehicle according to our novel design; and,

FIG. 2 is a perspective view thereof.

The broken lines are for illustrative purposes only and form no part of the claimed design.
